UNITED STATES PATENT OFFICE.

SIDNEY EUGENE WILSON, OF LAUREL, MISSISSIPPI.

EXPANSION VALVE.

Application filed February 17, 1927. Serial No. 169,068.

This invention relates to an expansion valve, especially adapted to be used in a refrigerating system, such, for example, as that shown in my co-pending application, Serial No. 122,632, filed July 15, 1926.

Some of the more important objects of the invention are to provide an expansion valve of this type, which is simple and inexpensive in construction and reliable in operation, and 10 which will maintain in a given degree of vacuum on the low pressure side at all times; to provide a device which permits visibility of operation; to provide a valve which may be used in either a wet or a dry system of refrigeration, and which will automatically control the pressures at a predetermined point.

The invention also embodies various novel features of construction which improve its operation, and result in greater efficiency. 20 All these features will be more fully explained in the following detailed description taken in connection with the accompanying drawings, showing the preferred embodiment of the same.

25 In the drawings:

Figure 1 is a vertical section through a valve constructed according to my invention, and adapted particularly for use in a flooded system.

30 Figure 2 is a horizontal section taken on the line 2—2 of Figure 1.

Figure 3 is a detail view of the valve element and means for supporting the same.

35 Figure 4 is a view similar to Figure 1, but showing the invention adapted to either a dry or a flooded system.

Figure 5 is a similar view showing the valve adapted particularly to a dry system.

The casing containing the valve may be 40 very simply constructed, either in one casting, or a plurality of castings rigidly secured together. In the form shown in Figures 1 and 2, the casing comprises an upper wall 10, and a lower wall 11 connected to each other by tie rods or bolts 12. The upper wall 10 is formed on its inner face with concentric channels 13, and opposite these channels the lower wall is formed with similar channels 14. Cylindrical walls 15 and 16 are seated in the channels 45 13 and 14, and are preferably composed of thick glass, so that the operation of the valve may be clearly observed. The inner wall 15 encloses a chamber 17, and between the walls 15 and 16 is an outer annular chamber 18.

50 The bottom wall 11 has a downward extension 19 defining a lower chamber 20

through which vapor passes on its way into the outer chamber 18, whence it passes to the compressor or condenser. Ports 21 connect the chamber 20 with the chamber 18. An inlet port 22 is formed in the wall 10 leading into the inner chamber 17, and is connected by a pipe 23 with the high pressure side of the system. The wall 10 is also provided with an outlet port 24 leading from the chamber 18, and a pipe 25 leads from the port 24 back to the intake of the compressor.

60 The lower portion 19 of the lower wall is formed with a reduced threaded extension 26, adapted to be attached to a refrigerating unit, 70 and extending downwardly within the extension 26 is a tube 27 secured to the inner portion of the wall 11, and providing an outlet from the inner chamber 17.

65 The passage of the refrigerant from the chamber 17 into the tube 27 is controlled by a conical valve 28. Located within the chamber 17 is an expandible and contractible bellows 29 adapted to be controlled by temperature or pressure. This bellows is provided 80 with a lower head 30 to which the valve 28 is secured, and an upper head 31 by which the bellows is supported.

75 The bellows 29 is supported by a stem 32, which is secured in a suitable manner to the head 31. In the present instance, the stem has a threaded connection with a collar 33 through which the bellows may be charged before it is mounted. The stem 32 is supported in a plug 34 secured to the wall 10, the stem having a threaded connection 35 with the plug, so that the bellows and the valve carried thereby may be adjusted up or down. The connection of the stem 32 with the plug is 90 closed by a suitable packing gland 36.

95 Studs 37 are secured to the inner face of the head 31, and support a check rod 38. The valve 28 has a stem 39 formed at its upper end with a hook 40 engaging the check rod 38, so as to positively prevent excessive expansion 100 of the bellows.

In applying the valve to a refrigerating system, the interior of the bellows 29 is charged with refrigerant, and the conical valve 28 is adjusted to a closed position before the compression is started. In other words, the normal position of the valve is closed, all pressures in the system being equal.

105 When compression is started, the inner chamber 17, which is connected with the high pressure side by the pipe 23, receives refrigerant under pressure. As the pressure in

- the chamber 17 increases, the bellows is compressed, and the valve member 28 is raised. This allows the liquefied refrigerant to pass downwardly through the pipe 27 to the boiler. This initial compression of the bellows is due to the increase of pressure outside the bellows. Subsequent compressions of the bellows may be from the joint action of pressure and temperature.
- 10 The next step in the action of the valve is absorption of heat by the volatile substance within the bellows, and the consequent expansion of the same which results in again expanding the bellows and closing the valve member 28. As the refrigerating process continues, the cold gas returning from the boiler to the space 20 and outer chamber 18 cools the liquefied refrigerant in the inner chamber 17. The gas within the sealed bellows 29 is thereby cooled, allowing the bellows to be again compressed, opening the valve member 28.
- 15 20 25 30 35 40 45

Thus, the action of the expansion valve allows the liquid refrigerant, together with whatever oil is carried over from the compressor, to flow as needed into the boiler. The level of the liquid will be maintained within the neck 26. The valve is so constructed that it is controlled partly by temperature and partly by pressure in such a way that the refrigerating liquid and lubricant will pass from the high side without passing any gas. It will pass the gas and any excess of lubricant from the boiler back through the outer chamber 18 to the compressor. The action is entirely automatic, and will continue without adjustment or attention.

Instead of the construction shown in Figure 1, the lower wall of the expansion valve casing may be formed, as shown at 11^a in Figure 4, and the port 21 may be connected by a pipe 41 with the refrigerating unit. This type may be used in either a flooded or a dry system.

In the form shown in Figure 5, the valve casing comprises an upper wall 10^b and a lower wall 11^b connected by tie rods or bolts 12. The wall 10^b is formed with only one circular channel 13, and the wall 11^b is formed with a similar channel 14 to receive the cylindrical glass wall 15. In this form, therefore, there is no outer chamber, but the refrigerant passes from the refrigerating unit directly back to the pump. This type of construction is for use in a dry system, and the pre-cooling effect of the refrigerant is not utilized.

From the foregoing description, it will be seen that I have devised an expansion valve assembly which is simple and practical in its construction, and in which the operation is plainly visible. This assembly is adapted to be used in any type of refrigerating system. The operation of the valve depends

upon the action of a single movable member, the bellows which supports it. It is instantly responsive to variations in temperature and pressure, and the required degree of vacuum is maintained on the low side of the system at all times. The valve prevents any accumulation of lubricant on the high side of the system as it allows oil to pass to the boiler where a uniform liquid level is automatically maintained. All lubricant that is in excess of the amount required to maintain the given liquid level, in the boiler, is returned to the crank case of the pump along with the returning gas. This circulation of the lubricating oil insures the smooth running of the refrigerating unit without any personal attention.

The valve is so constructed as to allow oil and liquid sulphur dioxide, or other refrigerant, to pass from the high side of the system, and will prevent any gas from passing with the liquid. This action maintains the pressure in the inner compartment of the valve, which is in reality a part of the high side of the system. The oil and gas, as it passes through the outer compartment 18 of the valve, on its way from the boiler to the crank-case of the pump, increases the efficiency of the system by its pre-cooling effect on the contents of the inner compartment. A vacuum is maintained in the boiler, but this does not in any way affect the operation of the valve.

The action of the valve, therefore, is controlled by the temperature and pressure within the bellows, in conjunction with the pressure and temperature outside the bellows in the inner chamber, which is a part of the high side of the system, while the gas and oil pass from the boiler to the pump through the outer chamber, which is a part of the low pressure side of the system. Conditions may be such that the temperature and pressure may work either in conjunction, or as distinct and separate agents in the operation of the system.

While I have shown and described the invention as best adapted for use in conjunction with the refrigerating system described in my above mentioned co-pending application, it is obvious that the same is capable of use in connection with any construction where a similar control by temperature and pressure is desired. It is also to be observed that various modifications may be made in the construction and arrangement of the various constituent parts without any material departure from the salient features thereof, or the recognized principles which characterize its operation. It is my purpose, therefore, to include all such modifications within the scope of the appended claims.

What is claimed is:

1. In an expansion valve assembly, the combination of a chamber having an inlet port in its upper wall and an outlet port in

its bottom wall, a bellows arranged vertically within the chamber and having an upper head and a lower head, means within the bellows to limit the longitudinal expansion thereof, means connected with the upper head for supporting the bellows, a valve secured to the lower head and controlling the outlet port in response to variations in temperature or pressure within the chamber, and 10 manually operable means for adjusting said bellows toward or away from the outlet port.

2. In an expansion valve assembly, the combination of a chamber having an inlet port and an outlet port, said outlet port being 15 at the bottom of the chamber, a bellows arranged vertically within the chamber and having an upper head and a lower head, means connected with the upper head for supporting the bellows, a valve secured to 20 the lower head and controlling the outlet port in response to variations in pressure within the chamber, a stop member connected to the inside of the upper head, and a hook connected to the inside of the lower head and 25 engageable with said stop member to positively limit the longitudinal expansion of the bellows.

3. In an expansion valve assembly, the combination of an inner chamber having an 30 inlet port and an outlet port, an outer chamber extending about the inner chamber and separated therefrom, means for connecting the inner chamber with the high pressure side of a refrigerating system, means connecting 35 the outlet port with the low pressure side, a valve for said outlet port, means connected to the valve within the inner chamber and operable by variations in pressure or temperature to actuate said valve, and means for connect-

ing said outer chamber respectively with the 40 low pressure side of the system and the compressor.

4. In an expansion valve assembly, the combination of an inner chamber having an inlet port to the upper part thereof and an outlet port from its bottom, a valve cooperating with the outlet port, means for controlling said valve in response to variations of 45 pressure within the inner chamber, means for connecting said inlet port with the high 50 pressure side of a refrigerating system, means for connecting said outlet port with the low pressure side, an outer chamber extending about the inner chamber and separated therefrom, means for connecting the 55 lower part of the outer chamber with the low pressure side of the system, and means for connecting the upper part of the outer chamber with the compressor.

5. In an expansion valve assembly, the combination of a casing comprising top and bottom walls with two transparent cylindrical concentric walls connecting the same to form inner and outer chambers, the inner chamber having an inlet port and an outlet 60 port, means for connecting said inlet port with the high pressure side of a refrigerating system, means for connecting the outer port with the low pressure side, a valve for said 65 outlet port, means for controlling the valve 70 in response to variations of pressure in the inner chamber, and means connecting the outer chamber respectively with the low pressure side of the system and with the compressor. 75

In testimony that I claim the foregoing as my own, I have hereto affixed my signature.

SIDNEY EUGENE WILSON.
